UNITED STATES PATENT OFFICE

FRED L. SEARS, OF NICHOLASVILLE, KENTUCKY

RAILWAY MAIL SERVICE CRANE

Application filed July 28, 1930. Serial No. 471,285.

This invention relates to a mail bag crane, the general object of the invention being to provide means whereby the bag can be easily and quickly attached to the arms of the crane, with spring means for causing the arms to hold the bag under tension and with means for moving the arms and their carrying member away from the track when the bag is caught by the catching device on the mail car.

A further object of the invention is to provide means for raising and lowering the arm carrying member to facilitate the placing of the bag on the arms and the positioning of the bag carrying parts to catching position.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is an elevation of the invention, showing the parts in catching position in full lines and in bag receiving position in dotted lines.

Figure 2 is a vertical sectional view through the sliding arm carrying member.

Figure 3 is a section on line 3—3 of Figure 2.

Figure 4 is a section on line 4—4 of Figure 2.

Figure 5 is a section on line 5—5 of Figure 2.

Figure 6 is a section on line 6—6 of Figure 2.

Figure 7 is a sectional view through the cap and the cable guide.

Figure 8 is a fragmentary rear elevation.

In these drawings, the numeral 1 indicates the base for the post 2 and 3 indicates a bracket slidably arranged on the post and carrying the housing 4 for the back supporting arms 5. The housing and bracket are each formed of two sections and a section of the housing is preferably formed with a sec-

tion of the bracket, as shown in the drawings, the sections being connected together by the bolts 6. The bracket is preferably formed with a flange at the top and bottom thereof, these flanges having a sliding fit on the post. 55 The bracket is also formed with the chambers 7 for receiving oil saturated waste or the like for lubricating the parts, the oil being introduced into the chambers through the oil holes 8. Each arm 5 is preferably of the cross sectional shape shown in Figure 5 and is of arc shape, as shown in Figures 1 and 2. Each arm has its vertical part pivoted in the housing, as shown at 9, so that the arm can swing about a horizontal axis and the outer 60 ends of the arms are formed with the notches 10 for receiving the loops at the ends of the mail bag A so that the bag is supported in vertical position between the arms. 65

A plunger 11, actuated by a spring 12, has 70 its head engaging the rounded inner ends of the arms, these ends extending beyond the pivotal points so that the spring of the plunger will cause the arms to move away from each other and thus exert pressure on 75 the bag. The plunger operates in a cylindrical chamber 13 formed at the center of the housing with the stem of the plunger extending into a small cylindrical chamber 14 formed in the bracket between the oil chambers 7. 80

A longitudinally extending rib 15 is formed on a portion of the rear part of the post and a roller 16 is arranged at the top of the rib. When the parts are in bag 85 holding position, a small notch 17 in the lower part of the bracket at the rear part thereof will receive a portion of the roller 16 so that the parts are frictionally held in position, whereby the device on a mail car can catch 90 the bag. The force of the catching operation will cause the bracket to swing in the direction the train is moving so that the roller will ride out of the notch on to the helicoidal surface of the notch 18 formed in the lower 95 end of the bracket. One of these notches is formed on each side of the bracket, and each notch is formed with a straight wall which will act as a stop for the swinging movement of the bracket when the roller en- 100

gages said straight wall. A cable 19 passes through the guiding passage 20 formed in the guiding head 21 which is formed with the cap 22 rotatably arranged on the top of the post and one end of this cable is connected by the link 23 with the top of the housing 4 and its other end has a handle forming ring 24 attached thereto. Thus by pulling upon the cable, the bracket and housing are raised so that the notched part 18 of the bracket 10 can be raised above the roller 16 and the bracket and housing turned to place the arms in a rearward position so that a groove 25 in the bracket will come into register with the roller 16 and the rib 15 which enables 15 the bracket and the parts associated therewith to be lowered into the dotted line position shown in Figure 1. A stop pin 26, carried by the post, will engage one of the notches 18 and limit the downward movement of the bracket, as shown in Figure 1. A new bag can then be placed on the arms and then the parts raised and turned to place the bag in catching position.

20 A weather guard casing 27 is attached to the upper arm and covers the upper opening in the housing so as to prevent rain or snow entering the housing, it being seen that the ends of the housing are formed with the openings 28 through which the arms pass.

25 From the foregoing it will be seen that I have provided simple means for holding a mail bag and means for moving the parts from catching position to a position where the bag can be attached to the device, with 30 means for automatically swinging the arm carrying means to a position at one side of the post when the bag is caught by the device on a train.

35 It is thought from the foregoing description that the advantages and novel features of the invention will be readily apparent.

40 It is to be understood that changes may be made in the construction and in the combination and arrangement of the several parts, provided that such changes fall within the scope of the appended claims.

What I claim is:—

45 1. A mail bag crane, comprising an upright, a member supported on the upright, a housing carried by the member, upper and lower arms pivoted in the housing and having means at their outer ends for supporting a mail bag between them, spring means engaging the inner ends of the arms for moving the arms away from each other to exert pressure on the bag, said member being rotatably and slidably arranged on the upright, means for frictionally holding the member against rotary movement with the arms holding the bag in catching position whereby the member will be swung to one side of the upright when the bag is caught and means for lowering and raising the member.

50 2. A mail bag crane, comprising an up-

right, a member supported on the upright, a housing carried by the member, upper and lower arms pivoted in the housing and having means at their outer ends for supporting a mail bag between them, spring means engaging the inner ends of the arms for moving the arms away from each other to exert pressure on the bag, said member being rotatably and slidably arranged on the upright, means for frictionally holding the member against rotary movement with the arms holding the bag in catching position whereby the member will be swung to one side of the upright when the bag is caught, means for lowering and raising the member, such means comprising a cap rotatably arranged on the upright and a cable guided in the cap and connected with the housing.

55 3. A mail bag crane, comprising an upright, a member supported on the upright, a housing carried by the member, upper and lower arms pivoted in the housing and having means at their outer ends for supporting a mail bag between them, spring means engaging the inner ends of the arms for moving the arms away from each other to exert pressure on the bag, said member being rotatably and slidably arranged on the upright, means for frictionally holding the member against 60 rotary movement with the arms holding the bag in catching position whereby the member will be swung to one side of the upright when the bag is caught, means for lowering and raising the member, such means comprising a cap rotatably arranged on the upright, a cable guided in the cap and connected with the housing.

65 4. A mail bag crane, comprising an upright, a member supported on the upright, a housing carried by the member, upper and lower arms pivoted in the housing and having means at their outer ends for supporting a mail bag between them, spring means engaging the inner ends of the arms for moving the arms away from each other to exert pressure on the bag, said member being rotatably and slidably arranged on the upright, means for frictionally holding the member against 70 rotary movement with the arms holding the bag in catching position whereby the member will be swung to one side of the upright when the bag is caught, means for lowering and raising the member, such means comprising a cap rotatably arranged on the upright, a cable guided in the cap and connected with the housing.

75 5. A mail bag crane, comprising an upright, a member supported on the upright, a housing carried by the member, upper and lower arms pivoted in the housing and having means at their outer ends for supporting a mail bag between them, spring means engaging the inner ends of the arms for moving the arms away from each other to exert pressure on the bag, said member being rotatably and slidably arranged on the upright, means for frictionally holding the member against 80 rotary movement with the arms holding the bag in catching position whereby the member will be swung to one side of the upright when the bag is caught, means for lowering and raising the member, such means comprising a cap rotatably arranged on the upright and a cable guided in the cap and connected with the housing.

85 6. A mail bag crane, comprising an upright, a member supported on the upright, a housing carried by the member, upper and lower arms pivoted in the housing and having means at their outer ends for supporting a mail bag between them, spring means engaging the inner ends of the arms for moving the arms away from each other to exert pressure on the bag, said member being rotatably and slidably arranged on the upright, means for frictionally holding the member against 90 rotary movement with the arms holding the bag in catching position whereby the member will be swung to one side of the upright when the bag is caught, means for lowering and raising the member, such means comprising a cap rotatably arranged on the upright, a cable guided in the cap and connected with the housing.

95 7. A mail bag crane, comprising an upright, a member supported on the upright, a housing carried by the member, upper and lower arms pivoted in the housing and having means at their outer ends for supporting a mail bag between them, spring means engaging the inner ends of the arms for moving the arms away from each other to exert pressure on the bag, said member being rotatably and slidably arranged on the upright, means for frictionally holding the member against 100 rotary movement with the arms holding the bag in catching position whereby the member will be swung to one side of the upright when the bag is caught, means for lowering and raising the member, such means comprising a cap rotatably arranged on the upright, a cable guided in the cap and connected with the housing, a longitudinally extending rib on the upright, a groove in the member engaging the rib when the member is given a half revolution on the upright and a stop for 105 limiting the downward movement of the member.

In testimony whereof I affix my signature.

FRED L. SEARS.
